UNITED STATES PATENT OFFICE.

ARTHUR C. GAYNOR AND EDWIN G. GAYNOR, OF STRATFORD, CONNECTICUT; SAID EDWIN G. GAYNOR ASSIGNEE TO SAID ARTHUR C. GAYNOR.

ELECTRIC BELL.

Application filed April 20, 1923. Serial No. 633,884.

To all whom it may concern:

Be it known that we, ARTHUR C. GAYNOR and EDWIN G. GAYNOR, citizens of the United States, and residents of Stratford, county of Fairfield, State of Connecticut, have jointly invented certain new and useful Improvements in Electric Bells, of which the following is a specification.

This invention relates to an electric bell and more particularly to an electric striking or ringing device for bells.

An object of the invention is to provide a bell of simple and cheap construction having a minimum of parts and requiring a minimum of connections and fastenings in its assembly. Other objects of the invention are to provide a bell operating mechanism which requires a small number of magnets for its operation, which may be readily assembled and taken apart and readily adjusted, and which forms a self contained unit in the cover for the mechanism. A further object of the invention is to provide a bell device in which the exterior of the bell is not disfigured by the striking of the hammer.

With these and other objects in view the invention comprises the device described and set forth in the following specification and claims.

The various features of the invention are illustrated in the accompanying drawings in which:

Fig. 1 is a perspective view of a bell device embodying a form of the invention, the cover of the actuating mechanism being removed and indicated by dotted lines.

Fig. 2 is a top sectional view of the bell taken on line 2--2 of Fig. 3.

Fig. 3 is a vertical sectional view of the device taken on line 3--3 of Fig. 2.

Fig. 4 is a side view, partly in section of a preferred form of striking hammer, and

Fig. 5 is a front view of the hammer shown in Fig. 4.

In our present invention, the hammer operating or striking mechanism for the bell is mounted in a cover, which is mounted in any suitable manner on a base to bring the hammer into proper striking position. The various elements of the mechanism within the cover are mounted on a frame which fits snugly into the cover and, when thus fitted serves to hold the elements of the mechanism in their proper position. This

frame is formed of a sheet of metal cut and bent to form a back and sides and positioning lugs. The front of the frame is formed of a strip or slab of insulating material having a contact and binding screw. 60 An electro-magnet is mounted on the back of the frame and connected to the binding screw and the contact. A striking or hammer arm operating also as an armature is mounted within the frame and is pivoted in 65 notches in the sides of the frame by means of lugs which extend from the end of the arm and are held in the notches by the walls of the cover when the mechanism is inserted into the cover. The striking or 70 clapper arm projects through the cover and under the bell so as to strike the inner edge of the bell when the mechanism is set into operation.

Referring more particularly to the accompanying drawings, the actuating mechanism embodying the invention is illustrated in connection with a bell 10 mounted on a base 12 of any usual or suitable construction. The actuating mechanism is mounted within 75 a cover 14 mounted on the base 12 in any suitable manner as, for example, by means of lugs 16 extending from the corners of the cover through openings 18 in the base.

The main elements of the mechanism are 80 mounted on a frame 20, which is assembled and mounted in the cover and one face of which fits against the side wall 21 of the cover 14 and is held tightly against the wall 21 of the cover by means of a core 22 of an 90 electro-magnet 24 mounted on the back of the frame and spanning the distance from the back of the frame to the opposite or rear wall 25 of the cover. The frame 20 is formed of a sheet of metal, preferably brass, 95 stamped to form a back portion 26, a number of upper side members 28, lower side members 30 and spacing lugs 32 and 34 extending from the back to the upper wall of the cover and to the base, respectively. The 100 front edges of the side members 28 and 30 are notched to receive a front plate or slab of insulating material 36 notched to fit into the notches of the side plates. The frame is shaped and adapted to fit into the front 105 part of the cover with the slab 36 against the wall 21 and is held tightly in position against the front wall 30 of the cover by means of the electro-magnet core 22 mounted on the rear face of the back 26 of the frame. 110

The sheet of metal forming the frame 26 is also bent to form a pair of lugs or flanges 38 and 40 on which is pivotally supported an armature arm 42 which extends under the bell 10 and is provided with a striking hammer 44 positioned to strike the inner edge of the bell as the arm is vibrated. The hammer 44 may be mounted on the armature arm 42 in any suitable manner, preferably by means 10 of a stem 45 projecting through and peened or headed over an opening in the end of the arm. The hammer arm is pivoted on the lugs 38 and 40 by means of a pair of lugs or projections 46 projecting sidewise from the end of the arm and fitted into notches 48 in the flanges 38 and 40. When the frame is fitted into the cover 14 the open ends of the notches 48 are closed by the side walls of the cover and hold the armature arm 42 in 20 position.

The armature arm 42 is pressed toward the front portion 36 of the frame by means of a spring 50 mounted in a recess 52 in the core 22. On the front face of the armature arm 42 is mounted a contact leaf or spring 54, attached to the arm at one end by means of a rivet 56 and provided at the opposite, free end with a contact bead 58 which is brought, by the pressure of the spring 50 25 against a contact screw 60 mounted on and extending through a bushing 62 in the insulating slab 36. The pivoted end of the armature arm 42 is provided with a pair of longitudinal slits 63 and the position of the arm between these slits is bent backwardly as at 64 to cause the free end of the leaf to project forwardly from the face of the arm. The screw 60 projects outwardly through an opening 65 in the cover 14, from which it is 30 insulated by the slab 36, and is provided with a lock nut 66 so arranged that the position of the screw may be adjusted and locked.

The electro-magnet 24 is connected to the bushing 62 by means of a wire 68 and, at its opposite end is connected by a wire 70 to a bushing 72 mounted in the slab 36. A binding screw 74 is mounted in the bushing 72 and extends outwardly through an opening 76 in the cover 14, from which it is insulated by means of a washer 78 of insulating material. Through this wiring an electrical connection is provided from a source of electricity through a lead wire 80 connected to the binding post 74 and through the wire 70, electro-magnet 24 and wire 68 to the screw contact 60. When the contact 58 touches the screw contact 60 the circuit is completed through the leaf 54 and arm 42 to the cover 14 with which the arm 42 and frame 26 contact. The cover 14 is provided with a binding screw 82 to which a lead wire 84 may be connected to return the current to the source of electrical energy. The electro-magnet is thus energized, attracting the arm 45

42, acting as an armature, breaking the contact connection 58-60, thus de-energizing the magnet and permitting the armature arm to be thrown by the spring 50 to again establish the connection through the contacts 70 58-60 and repeat the operations. The arm 42 is thus set into rapid vibrations in the usual manner and the bell rung.

As changes of construction could be made within the scope of our invention, it is intended that all matter contained in the above description or shown in the accompanying drawing be interpreted as illustrative and not in a limiting sense.

Having thus described our invention, what we claim as new and desire to secure by Letters Patent is:

1. A device of the kind described which comprises, a frame having a pair of lugs with notches opening endwise of said frame, 85 a hammer arm extending through said frame and having projecting pivot pins extending into said notches and means retaining said pins in said notches.

2. A device of the kind described which comprises, a frame having a pair of lugs with notches opening endwise of said frame, a hammer arm extending through said frame and having projecting pivot pins 90 extending into said notches, and a cover fitting over said frame and closing the ends of said notches.

3. A device of the kind described which comprises, a frame having a pair of lugs with notches opening endwise of said frame, 100 a hammer arm extending through said frame and having projecting pivot pins extending into said notches, an electro-magnet mounted on one face of said frame, a spring between said electromagnet and 105 said armature arm, and a cover enclosing said frame and electro-magnet and closing the ends of said notches.

4. A device of the type described which comprises, a hollow, channel shaped frame, 110 an electro-magnet mounted on the outer surface of one side of said frame, an armature pivoted to, and extending within, said frame, an insulated contact on said frame, a spring pressing said armature against said 115 contact, and a connection between said contact and one end of the winding of said electro-magnet.

5. A device of the type described which comprises, a cover, a frame mounted in said cover, said frame having a pivot notch, an armature arm extending within said frame and pivoted in said notch, an electro-magnet mounted on said frame within said cover, an insulated contact on said frame 120 connected to said electro-magnet, a contact on said armature arm and a spring between said magnet and said armature arm pressing said contacts together.

6. A device of the type described which 130

comprises, a frame having a metallic back and sides and a front of insulating material, a pair of notches in one end of said sides, an armature arm extending through said frame and having pivot pins mounted in said notches, means retaining said pins in said notches, an electro-magnet mounted on the back of said frame, terminals on said insulating front connected to said electro-
magnet, one of said terminals having a contact point, a spring between said electro-magnet and said arm pressing said armature arm to said contact point and an electrical connection from said armature arm.
7. A device of the type described which comprises, a cover, a frame fitting the front portion of said cover, an electro-magnet extending between said frame and the rear wall of said cover, an armature arm pivoted
in notches in one end of said frame and extending through said frame and the opposite end of said cover, a spring between said electromagnet and said arm, insulated terminals on said frame connected to said electro-magnet, one of said terminals having a contact point contacted by said armature arm in a direction opposite said spring, the other contact having a binding post, and a

binding post on said cover in electrical connection with said armature arm. 30

8. A device of the type described which comprises, a channel shaped frame having a pair of aligned notches in opposite edges at one end, a hammer armature arm extending through the channel of said frame and having pintles journaled in said notches, means retaining said pintles in said notches, an electro-magnet mounted on an external face of said frame, and a spring confined between said magnet and said hammer armature arm. 35 40

9. A device of the type described which comprises, a channel shaped frame having a pair of aligned notches in opposite edges at one end, a hammer armature arm extending through the channel of said frame and having pintles journaled in said notches, an electro-magnet mounted on an external face of said frame, a spring confined between said magnet and said hammer armature arm, 45 and a cover enclosing the walls of said frame, and the outer end of said electro-magnet. 50
